UNITED STATES PATENT OFFICE.

ARTHUR C. SCHROEDER, OF SYRACUSE, NEW YORK.

INDICATING SIGNAL FOR VEHICLES.

Application filed December 28, 1920. Serial No. 433,574.

To all whom it may concern:

Be it known that I, ARTHUR C. SCHROEDER, a citizen of the United States, and resident of Syracuse, in the county of Onondaga, 5 and State of New York, have invented a new and useful Improvement in Indicating Signals for Vehicles; of which the following is a specification.

The object of my invention is to provide 10 an indicating signal provided with "stop," "warning" and "right" and "left" direction symbols, together with means for illuminating any predetermined symbol, when so desired.

15 A further object is to provide an indicating signal in which the stop symbol will be automatically illuminated when the brake is applied.

20 A further object is to provide certain means whereby the license number plate will be illuminated by the illuminating device for the "warning" symbol and by the illuminating device for the "stop" symbol.

A still further object is to provide certain 25 improvements in the construction, form, arrangement and operation of the signal, whereby the objects above set forth may be easily and simply obtained.

30 A practical embodiment of my invention is represented in the accompanying drawings, in which,

Fig. 1 represents the casing of the device in front elevation.

Fig. 2 represents a section taken in the 35 plane of the line II—II of Fig. 1.

Fig. 3 represents a section taken in the plane of the line III—III of Fig. 2.

Fig. 4 represents a detached view of the 40 foot brake lever and the parts of the electric lighting system controlled thereby.

Fig. 5 represents a detail view of the manually operated switch for controlling the illumination of the "right" and "left" direction symbols.

45 Fig. 6 represents a diagrammatic view of the lighting circuit for the symbol illuminating devices.

Fig. 7 represents in diagram, the "right" direction symbol illuminated.

50 Fig. 8 represents in diagram the "left" direction symbol illuminated.

Fig. 9 represents in diagram the "stop" symbol illuminated.

55 Fig. 10 represents in diagram the "warning" symbol illuminated.

The casing comprises the oblong back wall 1 and the encircling wall 2. The interior of the casing is divided by the longitudinal partitions 3 and 4, and the transverse partition 5 into the "right" and "left" 60 end chambers 6 and 7 and into the front and back middle chambers 8 and 9.

The front plate 10 of the casing covers the fronts of the end chambers 6 and 7 and the front middle chamber 8. A suitable 65 visor 11 may be provided for the casing, if so desired.

The front and rear middle chambers 8 and 9 are provided with ports 12 and 13 through which the license number plate 14 may be 70 illuminated by either or both of the illuminating devices in said front and rear middle chambers, to be hereinafter described.

The front plate 10 is of glass and it may 75 be cut away or may be provided with translucent portions as shown, to form "right" and "left" direction symbols 15 and 16 and a "warning" symbol 17. The direction symbols are herein shown as arrow heads and the "warning" symbol is herein shown as an oblong rectangular figure connecting the arrow heads.

The transverse partition 5 is provided with a "stop" symbol. In the present instance this is arranged by cutting the symbol through the wall of the partition, and backing the letters with a sheet 18 of translucent material.

There is an illuminating device in each 90 of the chambers hereinabove referred to. In the present instance I have shown one electric lamp 19 in the front middle chamber 8, immediately back of the "warning" symbol 17. I have shown one electric lamp 20 in the 95 end chamber 6, back of the "right" direction symbol and one electric lamp 21 in the end chamber 7, back of the "left" direction symbol 16. I have shown two electric lamps 22 in the rear middle chamber 9, back of the 100 "stop" symbol in the transverse partition 5.

I have shown a wiring diagram in Fig. 6 by means of which the several lamps are lighted and extinguished as desired. In this diagram the foot brake operating lever is 105 denoted by 23, the manually operated switch by 24, the battery by 25 and the ground by 26. A wire 27 leads from the ground to the battery 25. A wire 28 leads from the battery to the switch 24. A wire 29 leads from 110

the wire 28 to the foot brake operating lever 23. A wire 30 leads from the contact 31 through the lamp 19 to the ground wire 32. This lever 23 is normally located in position to close the circuit through the lamp 19. A wire 33 leads from the contact 34 through the lamps 22 to the ground wire 32. A wire 36 leads from a contact 37 to the lamp 20 and from thence to the ground wire 32. A wire 38 leads from the contact 39 to the lamp 21 and from thence to the ground wire 32. A wire 40 leads from the contacts 41 and 42, to the lamp 19. A switch 43 is located in the wire 30 for manual control of the "warning" symbol 17.

In Fig. 4 I have shown a means whereby the application of the brake by the depression of the foot brake lever 23 will automatically extinguish the light 19 in the front middle chamber 8 and light the lamps 22 in the rear middle chamber 9 to illuminate the "stop" symbol through the "warning" symbol 17. This is accomplished by introducing a spring connecting arm 42 between the contact arms 31 and 34, whereby the depression of the lever will swing the arm 42 away from the contact arm 31 and into engagement with the contact arm 34. With the switch 43 closed, as at night, when the "warning" symbol should be illuminated at all times except when the "stop" symbol is illuminated; the swinging of the switch 24 into engagement with the contacts 37 and 42 will light the lamp 20 to illuminate the "right" symbol 15, it being understood that the lamp 19 remains lighted for illuminating the "warning" symbol 17. When the switch 24 is thrown over into engagement with the contacts 39 and 41, the lamp 21 is lighted for illuminating the "left" symbol 16, it being understood that the lamp 19 remains lighted for illuminating the "warning" symbol 17.

From the above description it will be seen that under normal conditions the "warning" symbol 17 will be illuminated by the lighted lamp 19. When the brake is applied to slow up the vehicle to swing the switch 23 from the contact 31 to the contact 34, the "warning" symbol illuminating lamp 19 is extinguished and the "stop" symbol illuminating lamps 22 are lighted, thus rendering the "stop" symbol visible through the "warning" symbol with which it is in alignment. With the switch 43 open, as in daylight, when the "warning" symbol illuminating device should be extinguished, except when the "warning" symbol is desired as a part of one of the direction symbols; the swinging of the switch 24 into engagement with the contacts 37 and 42 will light the lamps 19 and 20 to illuminate the combined "right" and "warning" symbols. When the switch 24 is swung into engagement with the contacts 39 and 41, the lamps 19 and 21 will be lighted to illuminate the combined "left" and "warning" symbols.

What I claim is:—

An indicating signal for vehicles including a casing having longitudinal and transverse partitions dividing the casing into end chambers and front and rear middle chambers, the transverse partition having a light transmitting "stop" symbol, a front plate having light transmitting "right" and "left" direction symbols in front of the end chambers, and a light transmitting "warning" symbol in front of the front middle chamber in alignment with the "stop" symbol and arranged to coact with either of the direction symbols, and means for illuminating a symbol or symbols.

In testimony, that I claim the foregoing as my invention, I have signed my name, this twentieth day of December, 1920.

ARTHUR C. SCHROEDER.
